UNITED STATES PATENT OFFICE.

WILLIAM G. JOPSON, OF WELLESLEY, MASSACHUSETTS, ASSIGNOR, BY MESNE ASSIGNMENTS, TO C. A. REED COMPANY, OF WILLIAMSPORT, PENNSYLVANIA, A CORPORATION OF DELAWARE.

SHIPPING TAG.

Application filed June 22, 1923. Serial No. 647,036.

This invention relates to shipping tags and has for its object to provide a reinforced construction for engagement by the usual string or wire by which the tag is attached 5 to an article and which shall be strong to resist tearing of the string or wire from the body of the tag. Such reinforcement should be of simple nature and be easily applied so as not to add materially to the cost of the 10 tag.

This invention, therefore, provides a single piece preferably of flat imperforate metal stock, which may be in the preferred construction of ribbon form, which spans a 15 portion of the stock of the tag, its ends being clinched therein, and intermediate these ends the piece being formed with a shoulder against which the string bears and which transmits the stresses between the body of 20 the tag and the string.

For a more complete understanding of this invention reference may be had to the accompanying drawings in which—

Figures 1, 2 and 3 are front, edge and 25 back elevations of the tag.

Figures 4 to 8 are each edge and rear elevations of different forms of reinforcement.

Referring first to Figures 1 to 4, 1 indicates the body of the tag which as shown is 30 of the usual flat form, though it is evident that it could be made in any suitable form such as an envelope or the like as is well known in the art. As shown the tag is provided with a pair of spaced perforations 2 and 3 therethrough back from one end thereof and between these perforations and the end of the tag and symmetrically disposed relatively thereto is a third perforation 4. The reinforcement 5, in the form of an imperforate metallic ribbon, is then made fast 35 to one face of the tag body by means of its ends 6 which are passed through slits in the tag and bent and clinched against the opposite face thereof. This strip or ribbon is of 40 a width to substantially bridge the space between the perforations 2 and 3 and extends toward and from the perforation 4 but lies wholly inwardly thereof. Intermediate its ends it is sharply bent outwardly away from 45 the face of the tag as at 7 to form a shoulder extending between the perforations 2 and 3. Between this shoulder and the end of the tag the ribbon may approach the tag with a gradual inclination as at 8. A string

or wire 10 has its opposite ends passed 55 through the perforations 2 and 3 so that its intermediate loop portion 11 bears on the outer face of the reinforcement immediately beneath the shoulder 7. Both ends of the string are then passed in the reverse direction through the perforation 4. Stress exerted between the string and the tag in a direction to pull the string therefrom then causes the loop 11 which passes behind the shoulder 7 to bear thereagainst, to transmit 60 the pulling strains to the tag body where the ends 6 pass through the slits therein. This furnishes an exceedingly strong construction. The reinforcements may be made from 65 cheap, preferably metallic material in ribbon form, which is merely cut into lengths 70 and bent to proper form.

In Figure 5 a slightly modified construction is shown in which the ends 6^a of the reinforcing strip are cut to form centrally disposed points which aid somewhat in inserting it in the tag slits but entail some waste 75 in the cutting of the reinforcements from the metallic strip.

In Figure 6 a further modification is 80 shown in which the ends 60 are cut along diagonal lines in reverse directions at opposite ends whereby the reinforcements are cut from the material by lines diagonal to the length thereof but without the formation of 85 waste and yet present pointed extremities for insertion through the slits of the tag.

In Figure 7 a still further modification is 90 shown in which the ends 61 are cut complementally in V formation so that two prongs are formed at one end and one at the other. The shoulder 71 is also formed differently, the stock above the shoulder being bent sharply downwardly to overlie the face of 95 the tag instead of approaching this face on a diagonal as at 8 in Figure 4.

In Figure 8 a still further modification is 100 shown in which strip or ribbon stock is not employed, but in place thereof a piece of imperforate sheet stock having three diverging arms 14, 15 and 16. A shoulder 70 is formed at the base of the arm 14, this shoulder being either of the form shown in Figures 4 or 7 as may be desired. The ends of the arms 14, 15 and 16 are then formed in any 105 suitable way to pass through slits in the tag body and bent against the opposite face thereof in the same manner as before. As

shown each of these arms terminates in a point 17, but of course it might be formed square as in Figure 4, or diagonally as in Figure 6, or as shown in Figure 7 if desired.

Having thus described certain embodiments of this invention it should be evident to those skilled in the art that many other changes and modifications might be made without departing from its spirit or scope as defined by the appended claims.

I claim:

1. A shipping tag having a body portion provided with a pair of spaced perforations therethrough, and a reinforcement passing between said perforations on one face of the tag and over which a loop of string having its ends passed through said perforations may bear, said reinforcement having a transverse shoulder against which the loop may bear.

2. A shipping tag having a body portion provided with a pair of perforations therethrough spaced from one end thereof, and a third perforation between said end and said pair of perforations, and an imperforate one-piece reinforcement extending between said pair of perforations on one face of said tag and lying wholly inwardly of said third perforation and over which may bear a loop of string having one end passed through each of said pair of perforations and both ends passed in the reverse direction through the third perforation.

3. A shipping tag having a body portion provided with a pair of perforations therethrough spaced from one end thereof, and a third perforation between said end and said pair of perforations, and an imperforate one-piece reinforcement extending between said pair of perforations on one face of said tag and lying wholly inwardly of said third perforation and over which may bear a loop of string having one end passed through each of said pair of perforations and both ends passed in the reverse direction through the third perforation, said reinforcement having portions passed through the body of the tag and clinched on the opposite face thereof.

4. A shipping tag having a body portion provided with a pair of perforations therethrough spaced from one end thereof, and a third perforation between said end and said pair of perforations, and a reinforcement extending between said pair of perforations on one face of said tag and over which may bear a loop of string having one end passed through each of said pair of perforations and both ends passed in the reverse direction through the third perforation, said re-

inforcement having a shoulder formed transversely thereof against which said loop may bear.

5. A shipping tag having a body portion provided with a pair of perforations therethrough spaced from one end thereof, and a third perforation between said end and said pair of perforations, and a reinforcement extending between said pair of perforations on one face of said tag and over which may bear a loop of string having one end passed through each of said pair of perforations and both ends passed in the reverse direction through the third perforation, said reinforcement having portions passed through the body of the tag and clinched on the opposite face thereof, and having a shoulder formed transversely thereof against which said loop may bear.

6. A shipping tag having a pair of spaced perforations therethrough, and a reinforcing strip extending between said perforations on one face of the tag, said strip having an outwardly extending shoulder laterally thereof between said perforations and behind which a loop of string having its ends passed through said perforations may bear.

7. A shipping tag having a pair of spaced perforations therethrough, and a reinforcing strip extending between said perforations on one face of the tag, said strip having an outwardly extending shoulder laterally thereof between said perforations and behind which a loop of string having its ends passed through said perforations may bear, said strip having its ends passed through slits in the tag and bent against the opposite face thereof.

8. A shipping tag having three triangularly arranged perforations therethrough adjacent one end thereof, and a metallic reinforcing member extending between two of said perforations and toward the third perforation on one side of said tag and bridging the space therebetween, the end portions of said member being passed through slits in said tag and bent against the opposite face thereof, said member being bent outwardly from the adjacent face of the tag to form a shoulder extending between said pair of perforations and behind which a loop of string having one end passed through each of said pair of perforations and both ends passed in the reverse direction through said third perforation may bear.

In testimony whereof I have affixed my signature.

WILLIAM G. JOPSON.
